(57) **CLAIM**

I claim the ornamental design for a rear facing car seat monitor, as shown and described.

DESCRIPTION

FIG. 1 is a Perspective view of a rear facing car seat monitor showing my new design;

FIG. 2 is a Front view thereof;

FIG. 3 is a Back view thereof;

FIG. 4 is a Left-side view thereof;

FIG. 5 is a Right-side view thereof;

FIG. 6 is a Top view thereof;

FIG. 7 is a Bottom view thereof; and,

FIG. 8 is another top view thereof, shown with the rear facing car seat monitor in condition of use.

The broken lines depict portions of the rear facing car seat monitor that form no part of the claimed design.
